UNITED STATES PATENT OFFICE.

HENRY W. STEEDE, OF WESTGATE, IOWA.

PORTABLE GRAIN-ELEVATOR.

1,135,735.

Specification of Letters Patent. Patented Apr. 13, 1915.

Application filed June 4, 1913. Serial No. 771,727.

To all whom it may concern:

Be it known that I, HENRY W. STEEDE, a citizen of the United States, residing at Westgate, in the county of Fayette and State 5 of Iowa, have invented a new and useful Portable Grain-Elevator, of which the following is a specification.

The present invention relates to improvements in portable grain elevators, the primary object of the present invention being 10 the provision of a novel form of elevator mechanism swingingly connected to the vehicle portion of the apparatus and disposed to be placed in such position so as to receive 15 the grain as the same is delivered from the inclined wagon body.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made without 25 in the scope of what is claimed without departing from the spirit of the invention.

In the drawings—Figure 1 is a side elevation of the complete apparatus taken from the elevator hopper side thereof. Fig. 2 is a 30 rear elevation of the same. Fig. 3 is a top plan view of the grain elevating mechanism and the rear portion of the vehicle body. Fig. 4 illustrates a modified construction of stack control.

Referring to the drawings, the numeral 1 designates the vehicle running gear which has disposed thereupon the prime mover 2, which is preferably an explosive or internal 35 combustion engine, the same having connected thereto the main drive belt 3, which is extended rearwardly of the vehicle and is connected through the pulley 3' to the transversely disposed shaft 4, said shaft 4 being journaled in brackets upon the rear 40 face of the short and long vertical standards 5 and 5' respectively, the standard 5' being shorter than the standard 5, the purpose of which will presently appear.

The belt 37 is driven from the shaft 4 and 50 through the pulley connection operates the transverse shaft 38, which is journaled at the rear portion of the main frame of the apparatus, there being a sprocket 39 keyed upon the shaft 38 and which through the 55 chain 40 and large sprocket 41 rotates the transversely disposed shaft 42. This shaft

42 is detachably connected to the shaft 43, the shaft 43 being slidably mounted and provided with the socket 44 for engagement with the shaft 42. The spiral conveyer hopper 45, is swingingly hung to the main frame of the machine through the medium of the post 50 and braces 46, 47, 48 and 49 so as to assume either the full line position as shown in Figs. 1, 2, and 3, or the dotted line 60 position as shown in Fig. 3 when the same is out of use.

The shaft 43 has keyed upon its outer end the sprocket 51, which transmits motion through the sprocket chain 53 to the sprocket 52, so that the spiral conveyer or screw 54 within the hopper 45 will convey the material or grain received from the inclined wagon, such wagon being so positioned as to dispose the end gate portion thereof above 70 the hopper 45 so that the grain may be dumped in the outer end thereof and transported by means of the feed screw to the left as viewed in Figs. 2 and 3 and into the fan or elevating casing 55, there being led 80 from said casing 55 the directing stock or conduit 56 which is as usual detachably connected to the fan casing 55.

Connected to the main frame of the vehicle and extending rearwardly therefrom 85 are the two receiving hooks 57 which are disposed to engage the underside of the hopper 45 when the same is in the dotted line position, Fig. 3, to maintain the same in collapsed position and out of the way 90 so that the machine may be readily transported.

As shown in Fig. 4, a pivoted hoisting beam or mast 60, connected at its lower end to the supporting arm 61, is provided. Its 95 outer free end carries the cradle 62, by means of which the stack 56' is connected for lowering and elevating, a hoisting cable 63 being provided to operate the beam 60. The cable 64 provides a means for extending 100 the telescopic stack 56' and thus provides a means for directing the grain to the desired point.

It is evident that with an apparatus of the present character, the same may be 105 moved from place to place, thus providing a portable grain elevator of a convenient size, and one which can be readily collapsed or folded to occupy a minimum amount of space during transportation.

What is claimed is:

The combination with a portable grain

elevator, of a portable frame, a prime mover, two superposed operably connected shafts journaled at the rear of the frame, one of said shafts being operably connected to the 5 prime mover, an elevating mechanism operably connected to the lower shaft, a hopper hingedly connected to the rear of the frame for movement to one side of, or to the rear of the frame, a cradle for receiving the hopper when the same is at the rear of the 10 frame, a shaft journaled longitudinally of the hopper for alinement with and connec-

tion to the upper shaft of the superposed shafts when the hopper is at one side of the frame, and a screw conveyer disposed in the 15 hopper and operably connected to the longitudinal shaft.

In testimony that I claim the foregoing as my own, I have hereto affixed my signature in the presence of two witnesses.

HENRY W. STEEGE.
